BOX STRAPPING TOOL

John Harold Webster, Newington, Conn., assignor
to The Stanley Works, New Britain, Conn., a
corporation of Connecticut

Application June 21, 1933, Serial No. 676,790

7 Claims. (Cl. 81—9.1)

This invention relates to a tool or machine by means of which bands or strips of metal or the like may be applied to boxes, packages, et cetera.

The aim of the invention is to provide a very simple, compact, durable and sturdy machine which is easy to operate and by means of which straps may be tightened, sealed and cut with the greatest facility.

My improved machine has various features of novelty and advantage, is relatively small and compact and yet capable of tightening bands about the boxes or packages under considerable tension, and is capable of applying relatively heavy and strong seals to the stretched strap with minimum effort on the part of the operator. The several levers or handles with which the tool is provided are conveniently placed, are readily operable, and do not interfere with one another in their operations.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings wherein is shown, for illustrative purposes, one embodiment 30 which the present invention may take,

Fig. 1 is a perspective view of my improved tool;

Fig. 2 is a side view thereof with the sealing mechanism shown by full lines in raised or with-drawn position and shown by dotted lines in lowered or operative position;

Fig. 3 is a top plan view of the structure, with parts in section;

Fig. 4 is a view taken generally longitudinally and vertically through the tool;

Fig. 5 is a transverse sectional view through the stretching or tightening mechanism, this view being taken substantially on line 5—5 of Fig. 4;

Fig. 6 is a front view of the machine;

Fig. 7 is a sectional view through the sealing mechanism, the same being shown in operated condition;

Fig. 8 is a top view of the forward end of the tool, with the sealing lever in operated position; and

Fig. 9 is a view of a complete seal which may be formed by the use of my mechanism.

Referring to the drawings in detail, A denotes generally a frame which has a large foot plate 10 adapted to rest upon a box or similar member

to which the strap is to be applied; a head or body portion having a pair of parallel side walls 11 and 12, a front wall 13 inclined upwardly and rearwardly, and a downwardly extending rear portion 14; and a heel plate 15 on the downwardly extending portion and located behind and in the plane of the foot plate 10 so as to also rest upon the box. The frame comprising the various portions described is preferably an integral casting. The right-hand side wall 11 of the frame arises 10 from the foot plate, the other side wall 12 of the front wall 13 being spaced above the foot plate in order to permit the strap to be inserted edge-wise from the left-hand side of the machine. The foot plate 10 has on its upper surface and adjacent its forward end, a pair of laterally spaced apart lugs 16 between which the strap is positioned so that it is properly aligned with the stretching and sealing instrumentalities. Behind these lugs, the foot plate has an opening 17 for 20 accommodating the sealing jaws, as hereinafter described more in detail. The body portion of the frame is provided on its front wall 13 with a dovetailed way 18 upon which is slidably mounted a housing B which carries the sealing mechanism.

For the purpose of stretching a strap about the container, there is provided a friction plug 21 carried by the foot plate 10 and a cooperating tightening wheel C journalled in the head between the side walls or cheeks 11 and 12. This wheel, in the present illustrated disclosure, includes two friction wheels or disks 22 having their edges serrated, as is usual, and an interposed ratchet disk 23 of slightly lesser diameter 35 than the friction disks, the several disks being secured together by dowel pins 24. The tightening wheel is mounted upon the eccentric portion 25 of an eccentric shaft 26 the opposite ends of which are journalled in the respective cheeks 40 or side walls 11 and 12. If desired, a bushing 27 may be interposed between the eccentric and the tightening wheel. For the purpose of turning the eccentric shaft to thereby raise and lower the tightening wheel into and out of engagement with the overlapping strap ends which overlie the plug 21, the eccentric shaft is provided, preferably at its left-hand end, with a crank handle 28. The handle may be secured to the end of the shaft by a screw 29. For the purpose 45 of limiting the extent of movement of the crank handle, the hub portion thereof is cut away so as to provide two angularly spaced apart stops 30 and 31 which are adapted to engage a pin 32 fixed to the head. When the handle is in the 50

position shown in Fig. 1, the shoulder 30 engages the stop or pin 32 and the wheel is elevated. When the handle is in the position shown in Fig. 2, the wheel is lowered into operative relation with the strap. For the purpose of rotating the friction wheel with a step by step motion, there is provided a rearwardly extending tightening handle 33 the forward end of which is forked so as to straddle the friction wheel. This handle is journalled on the bushing 27, as will be seen most clearly from Figs. 4 and 5. Pivoted on the handle, as at 34, is a tightening pawl 35 having on its free end a tooth 36 adapted to cooperate with the ratchet teeth of the ratchet disk 23. This pawl is normally urged into engagement with the ratchet disk by a spring 37. Located between the cheeks 11 and 12 and pivoted on a pin 38 is a holding pawl 39 having a tooth 40 cooperating with the teeth of the ratchet disk. This pawl is normally urged into engagement with the ratchet disk by a spring 41. For the purpose of disengaging the tightening pawl 35 from the ratchet disk, this pawl may have a rearwardly extending tail piece 42 below which is the forward end of a release lever 43 pivoted, as at 44, to the tightening handle 33 and having an operating stem 45 extending upwardly through an opening in the handle. The friction plug 21 is screwed into an opening in the foot plate 10 as particularly illustrated in Figs. 4 and 5 so that the plug is vertically adjustable with respect to the friction wheel. For the purpose of holding the plug in adjusted position, the lower end thereof may be provided with cross slots 46 in which is adapted to selectively engage the rear end of a spring 47 located in a groove 48 in the bottom surface of the foot plate. The forward end of the spring is anchored in place by a screw 49. These slots may also accommodate a tool such as a screw driver to adjust the plug when the spring 48 is removed from the slot.

Referring now to the sealing mechanism, the housing B is preferably in the form of a casting or block having a cylindrical bore 50 extending down to a bottom wall 51. The casting is slotted at each side so as to accommodate the sealing jaws 52 and toggle links 53. Extending rearwardly from the sides of the housing are webs 54, and these webs have opposed dovetailed grooves 55 for accommodating the way or rib 18. Mounted for reciprocation in the bore 50 is a generally cylindrical rack bar 56 having rack teeth 57 on its rear side. The lower end of the rack bar is transversely slotted so as to accommodate the upper ends of the links 53. These links are pivoted to the rack bar, as by means of pins 58. The links are pivotally connected to the upper ends of the sealing jaws 52 by pins 59. These jaws are pivoted between their ends on pins 60 carried by the housing B. Located between the jaws is a complementary sealing member or anvil 61. This anvil, in the present instance, is secured, as by means of a screw 62, to the under side of the bottom wall 51. The jaws and the anvil may be constructed and correlated so as to form a seal of any suitable type, they here being shown as being arranged to form a seal S, such as illustrated in Fig. 9. To this end, the anvil is provided, adjacent each side edge, with depending V-shaped teeth 63, and the jaws are provided with grooves 64 adapted, when the jaws are moved to the operated position shown in Fig. 7, to register with and receive the respective projections 63.

75 The housing B also carries a knife D for scor-

ing the strap just forwardly of the seal so that, after the seal is formed, the strap may be bent back and forth a few times along the line on which it has been weakened thereby breaking the portion of the strap attached to the box from the roll from which the strap is taken. In the present instance, this knife has a head portion 70 located just forwardly of the anvil and a cylindrical stem portion 71 mounted for reciprocation in a cylindrical opening 72 in the bottom wall 51 of the housing. At the lower end, the knife has two spaced apart aligned knife edges 73 which are adapted to be forced partially through the strap. The rack bar carries an adjustable screw 74, the lower end of which is adapted to engage the top of the stem 71 as the sealing members are completing the seal. The knife is normally urged to a raised position by a spring 75, the forward end of which engages in an opening 76 adjacent the upper end of the stem 71. The rear end of the spring is secured to the housing by a screw 77.

For the purpose of sliding the housing B, together with the sealing and cutting instrumentalities carried thereby, into and out of operative position, and for operating these instrumentalities after they have been brought to operative position, a relatively long lever E is provided. This lever is preferably an integral member having a pair of parallel spaced apart side arms 80 and a grip portion 81 at the rear ends of the arms and connecting the same. The space in the lever E between the arms thereof is adapted to accommodate the stretcher operating handle 33. The forward ends of the arms straddle the housing B and the arms between their ends are adapted to straddle the rear portion 14 of the frame when the lever E is in the position shown in the drawings. The forward end of the lever E is connected to a shaft journalled in the housing B rearwardly of the rack 56. This shaft, in the present instance, includes a pair of bushings 82 respectively journalled in the webs 54 and held together by a threaded rod 83. About this rod and between the bushings is a segmental gear 84, the teeth of which are adapted to mesh with the teeth 57 of the rack bar. The inner ends of the bushings are provided with lugs 85 adapted to take into correspondingly shaped notches in the hub of the gear so that the bushings, the threaded rod 50 or screw and the gear or pinion will turn in unison. The outer ends of the bushings have non-circular heads 86 engaging in grooves 87 in the forward ends of the arms 80 so that, when the lever is turned, the bushings and gear will turn therewith. The arms of the lever, just rearwardly of the forward ends thereof, have, on their opposed faces, inwardly extending lugs or fulcrums 88 adapted to engage on the upper edges of the side walls or cheeks 11 and 12 of the frame 60 rearwardly of the front wall of the frame. In order to limit the extent of movement of the lever when it is thrown into the full operative position shown by dotted lines, Fig. 2, one of the lugs 88 is provided with an adjustable screw 89 adapted to engage the top of the housing. It may be found desirable to releasably hold the lever in the inoperated position shown in Figs. 1 and 3 and, to this end, there may be provided in the rearwardly extending portion of the frame bullet catches comprising balls 90 between which is a spring 91. The arms 80 are grooved, as at 92, so as to receive these balls. The housing B is normally urged towards operative position by a spring 93 particularly illustrated in Fig. 5 hav-

ing its central portion in the form of a coil positioned about a hub 96 through which the shaft 26 extends. The rear end of the spring is looped, as at 97, over the cheek 11. The forward end 5 of the spring engages a shoulder 98 on the right-hand side of the housing B. At the upper right-hand corner of the front wall 13 of the head is a stop lug 99 which overhangs the forward end of the spring. As the forward end of the spring 10 bears upon the shoulder 98, the housing is normally urged downwardly. The housing is prevented from being accidentally withdrawn upwardly off of the way 18, by the engagement of the forward end of the spring against the stop lug 15 99.

The operation of the device is briefly as follows: the seal S is threaded onto the strap or band X and the strap then passed about the package or box Y. The free end of the strap is then threaded through the seal. The box strapping tool is then positioned upon the box, and the overlapping strap portions are moved edgewise to a position where these overlapping portions are interposed between the friction plug 21 and the friction wheel 25. The heel plate rests upon the strap, and the overlapping strap portions are positioned above the foot plate. The crank handle 28 is then thrown forwardly to the position shown in Fig. 2, to thereby turn the eccentric 25 and thus lower 30 the friction wheel into engagement with the upper overlying strap portion. The handle 33 is now oscillated up and down to thereby turn the friction wheel in a direction to move the overlying strap portion with respect to the underlying one, 35 thus stretching the strap about the box. It will be understood that, when the handle 33 is moved upwardly, the paws 39 holds the friction wheel against rotation counterclockwise, referring to Fig. 4 and, when the handle is moved downwardly, the friction wheel is turned through the pawl 35 clockwise, that is, in a direction to exert a pull upon the strap. In the event the desired tension 40 on the strap is obtained when the handle 33 is in raised position, the release lever 43 may be turned through the operating knob 45 to withdraw the tightening pawl from the ratchet disk and then the handle may be lowered to the normal position shown in Fig. 4. In this position, the handle rests upon the edge 14 of the frame A. 45 It will further be seen that, during the operation of the handle 33, the lever E is out of the way although these levers cross. The strap having now been tightened, and the seal having been properly positioned with respect to the opening 50 17 in the foot plate, the lever is thrown forwardly from the full line position to the broken line position shown in Fig. 2. During the initial swinging movement of the lever E, it will fulcrum on the shoulders provided for by upper edges of 55 the cheeks 11 and 12, and the forward ends of the lever are lowered, with the result that the housing B will slide downwardly and forwardly on the way 18 from the withdrawn position shown by full lines, Fig. 2, to the operative position shown by broken lines in that figure. The seal is now straddled by the lower ends of the sealing jaws. On continued movement of the lever E, the teeth of the gear 84 mesh with the teeth 57 of the rack, whereupon the rack is moved downwardly and, through the links 53, the sealing jaws are moved to the position shown in Fig. 7 so as to form the seal. As the lever approaches the end of its operative stroke, that is, as the sealing operation is being completed, the screw 74 carried 60 by the rack will engage the stem 71 of the knife, 65 thereby forcing the edges of the knife against the upper overlapping strap portion forwardly of the seal. The knife makes two score marks or lines of weakness in the strap for the purpose previously stated. The sealing and scoring operations now having been completed, the lever is swung back to its normal position shown in Fig. 1, thereby first withdrawing the sealing jaws from the seal and then raising the housing B, together with the instrumentalities carried thereby. The crank 10 handle 28 is then turned back to the position shown in Fig. 1 so as to raise the friction wheel. During the operation of tightening the strap, the operator may use one hand to oscillate the lever 33, and with the other hand he may grip the 15 handle 28 so as to hold the device steady. During such time the lever is in closed relation to the handle 33, the rear end of the lever being below and out of the way of the rear or free end of the handle 33. The longitudinal slot or opening in 20 the lever E is of such length that when this lever is moved to and from the position shown in Fig. 1, it will clear the handle 33. During the operative stroke of the lever E, and particularly while forming the sealing operation, the operator may 25 grip and bear down on the handle 33 so as to hold the tool steady, the other hand being used to operate the lever E.

As many changes could be made in the above construction and many apparently widely different embodiments of this invention could be made without departing from the scope thereof, it is intended that all matter contained in the above description or shown in the accompanying drawings shall be interpreted as illustrative and not 35 in a limiting sense.

It is also to be understood that the language used in the following claims is intended to cover all of the generic and specific features of the invention herein described and all statements of 40 the scope of the invention which, as a matter of language, might be said to fall therebetween.

I claim as my invention:

1. In a box strapping tool, a frame, means carried by said frame for tightening the strap and including a rearwardly extending oscillatory handle; and sealing means including a housing supported by said frame forwardly of said tightening means for movement into and out of operative position, sealing members movably carried by said housing, and a lever for moving said housing into and out of operative position and for operating said sealing members; said lever being longitudinally slotted so as to accommodate said handle, said lever being swingable in the plane of oscillation of said handle and having an inoperative position in which it is rearwardly extending and in crossed relation with said handle. 45

2. In a box strapping tool, a frame having an upwardly and rearwardly inclined slideway at its forward end, means carried by said frame rearwardly of said slideway for tightening the strap and including an oscillatory handle; and sealing means including a housing slidably mounted on said slideway for movement into and out of operative position, sealing members movably carried by said housing, and a lever pivoted to said housing for moving said housing into and out of operative position and for operating said sealing members, interengaging means between said lever and frame whereby said lever is fulcrumed rearwardly of its pivotal connection with said housing, said lever being swingable from a rearwardly extending position to a forwardly extending position, said handle and lever being in 60 65 70 75

crossed relation when the latter is in its rearwardly extending position.

3. In a box strapping tool, a frame having an upwardly and rearwardly extending slideway at its forward end, strap tightening means carried by said frame rearwardly of said slideway and including a friction wheel and an oscillatory handle for rotating the friction wheel with a step by step movement; and sealing means including a housing slidably mounted on said slideway, sealing jaws movably carried by said housing, a lever pivoted to said housing, an operative connection between said lever and sealing jaws, and means on said lever adapted to rest upon said frame rearwardly of said slideway whereby said lever is fulcrumed on the frame during the operation of lowering the housing to operative position; said lever being swingable in the plane of oscillation of said handle from a rearwardly extending position to a forwardly extending position, said lever having a slot for accommodating said handle and being in crossed relation to said handle when the lever is in rearwardly extending position.

4. In a box strapping tool, a frame having an upwardly and rearwardly inclined slideway and shoulders rearwardly of said slideway, a housing mounted for sliding movement on said slideway and spring biased in one direction, sealing members movably carried by said housing, a lever pivoted to said housing, an operative connection between said lever and said housing and an operative connection between said lever and sealing members, said lever being arranged to fulcrum upon said shoulder during movement of said housing.

5. In a box strapping tool, a frame having an upwardly and rearwardly inclined slideway and shoulders rearwardly of the slideway, a housing slidably mounted in the slideway spring biased

in one direction, jaw members movably carried by the housing, a rack carried by the housing and operatively connected to said jaw members, a shaft pivoted on the housing, a segmental gear on the shaft and adapted to mesh with said rack, and a lever fixed to said shaft, said lever member being arranged to fulcrum on said shoulders to move said housing against the tension of said spring.

6. In a box strapping tool, a housing mounted for sliding movement into and out of operative position, jaw members movably carried by said housing, a knife member movably carried by said housing, a rack bar slidably carried by said housing and operatively connected to said jaw members, means carried by said rack bar and adapted to operate said knife to score the strap at the completion of the sealing operation, and a lever operatively connected to said rack bar for moving the same.

7. In a box strapping tool, a frame having a forwardly and rearwardly inclined slideway and shoulders rearwardly of the slideway, a housing slidably mounted in said slideway, jaw members movably carried by said housing, a rack slidably carried by said housing and operatively connected to said jaw members, a shaft journaled in said housing, a segmental gear on said shaft and adapted to mesh with said rack, and a lever fixed at its forward end to said shaft and having means rearwardly of the forward end adapted to rest upon said shoulders whereby said lever is fulcrumed on the frame during the operation of lowering the housing to operative position, said segmental gear being engaged with said rack after said lever has been swung to such an extent as to lower said housing to operative position.

JOHN HAROLD WEBSTER.
